UNITED STATES PATENT OFFICE.

JOSEPH H. WALKER, OF GRAND RAPIDS, MICHIGAN, ASSIGNOR OF ONE-HALF
TO WILLIAM H. POWERS, OF SAME PLACE.

BURIAL-CASKET.

SPECIFICATION forming part of Letters Patent No. 276,312, dated April 24, 1883.

Application filed October 24, 1882. (No model.)

To all whom it may concern:

Be it known that I, JOSEPH H. WALKER, of Grand Rapids, in the county of Kent and State of Michigan, have invented certain new and useful Improvements in Burial Caskets or Cases; and I do hereby declare that the following specification, taken in connection with the drawings furnished and forming a part of the same, is a clear, true, and complete description of my invention.

My said improvements relate to the tops of caskets or cases, and my object is to provide therefor a sliding face-lid which, when closed, will present a neat finish, corresponding with one or more immovable panels, as usually preferred, and also to so mount said sliding face-lid that a glass lid, whether sliding or otherwise, may be employed, if desired, in connection therewith.

In Letters Patent No. 228,836, issued to myself and William H. Powers June 15, 1880, we were the first to disclose a sliding face-lid and the combination of a sliding face-lid and a sliding glass lid, and also such an arrangement of the face-lid and the adjacent sliding ways that the glass lid could be employed or not, as might be desirable in each case. As heretofore devised by us, however, it was impossible to obtain a uniform exterior finish upon the top of the case or casket, because said prior face-lid, when closed, presented its upper surface in the plane of the under surface of the main portion of the top, and the construction and arrangement of the lid and the raceway in which the lid moved were such as would not practically permit the introduction of a top panel for harmonizing in effect with the sunken closed face-lid. To provide for such a finish with a panel or panels, as in a casket, or for a flush finish when no panels are used, as in plain coffins, it is necessary that the face-lid be flexibly mounted in raceways, so as to be capable of a vertical movement bodily in assuming or departing from its closed position; and so far as my knowledge extends I am the first to provide for such movements in a sliding face-lid, although I am well aware that sliding glass lids have been similarly arranged; but it is obvious that with such prior glass lids

it is usual and desirable to employ a close or face lid, and that the neat and uniform exterior finish now sought by me could not be obtained by any form of superimposed face-lid capable of being silently and readily applied and removed, and without the use of mechanical appliances, which constitute the principal advantages of sliding face-lids.

After fully describing a burial-casket embodying my improvements the features deemed novel will be specified in the several claims hereunto annexed.

Referring to the drawings, Figure 1 is a top view of the casket-top with the lid closed. Fig. 2 is a longitudinal central section with sliding lid, as in Fig. 1. Fig. 3 is a top view of sliding lid detached. Fig. 4 represents side and top views of spring-wireway detached. Fig. 5 is a lateral section of Fig. 1 through lid when closed. Fig. 6 is a lateral section of Fig. 1 through lid when open. Fig. 7 is a central longitudinal view of a modification without lid. Fig. 8 is a longitudinal section of sliding lid with spring attached.

As here shown, the casket-top A is of the molded-edge variety, has a fixed panel, a, and a sliding close or face lid, b, which is in area and finish a counterpart of the fixed panel, although said lid is preferably provided with exterior means for manipulating it, either in the form of a recessed thumb-piece, for instance, or a knob, as shown. The face-lid b slides horizontally in a raceway, c, beneath the fixed panel a, there being two of said raceways, one on each side, and lugs or projections d are provided on each edge of the lid for occupying said ways. At each side of the face-opening the raceways are vertically wider than they are beneath the fixed panel, so as to permit the lid to be moved upwardly, and thereby be in a position flush with the main upper surface of the fixed panel. At the head end of each raceway the lower or bearing surface is inclined upwardly, affording inclined planes, as at e, so that when the front lugs or projections, d, on the lid come into contact therewith the front end of the face-lid is lifted into and supported in the flush position occupied by it when closed. The rear lugs or projections, d, on

said face-lid, as shown in Figs. 1 to 6, inclusive, traverse or slide on the wireway *f*, and when the lid is in its closed position, said rear lugs respectively rest upon said springway *f*, which is bent to afford an inclined plane, as at *f'*, to correspond with the inclined planes *e* at the head ends of the ways *e*, before described, whereby the rear end of the face-lid is lifted while sliding forward into its closed position. Each *springway f* is preferably composed of wire bent into a form clearly indicated in Fig. 4, and the front end of it firmly occupies a lateral hole in the casket-top in the raceway at the side of the opening in the top, so that the adjacent rear lug, *d*, slides above said wires, and the rear end of said wireway firmly occupies a lateral hole in the casket-top below the raceway *c*, beneath the fixed panel, so that the front lug, *d*, slides below said wire when the lid is moved rearwardly. These wireways have a spring capacity in a vertical plane to enable them to be depressed when the rear lugs, *d*, advance with the lid into its closed position, and by resuming their normal condition said springways, when traversed by the rear lugs, lift the rear end of the face-lid into its proper position when closed, and cause said rear end to abut against the coincident edge of the opening, thus firmly locking the lid against longitudinal movement, but leaving said rear end free to be forced downwardly when the lid is to be moved backwardly. It will be seen that with this sliding face-lid there may be employed either the simple sliding glass lid or one also arranged to be lifted or lowered; or it may be hinged so as to be swung upwardly, and when desired the glass lid may be wholly dispensed with; but it is obvious that my construction and arrangement of the face-lid and its ways enable any form of glass lid to be readily applied beneath it for use therewith.

As the main feature of my invention involves a sliding face-lid having front and rear

side lugs and flexibly mounted on spring-wireways and in raceways, so as to be movable longitudinally and vertically, as described, it is to be understood that I do not limit myself to the precise construction and arrangement of the raceways and wireways shown and thus far described, because I have obtained similarly desirable results by employing in connection with each raceway, as an equivalent of the wireways and rear lugs, a bent spring, *g*, secured to the under side of the face-lid, at its rear end, and projecting longitudinally therefrom, as illustrated in Figs. 7 and 8. In this case I also employ the inclined or lifting surfaces *e* at the front or head end of the raceways for lifting the front end of the face-lid and wedging it into its closed position.

It will be seen that when the face-lid is closed it occupies a position and horizontal plane precisely corresponding with the fixed panel *a*, and that it cannot be distinguished therefrom except by the presence of the knob, and, so far as my knowledge extends, this desirable result in exterior finish in casket-tops has never before been obtained in connection with a sliding face-lid.

Having thus described my invention, I claim as new and desire to secure by Letters Patent—

1. The combination, with the sliding lid provided with the front and rear lugs, of the raceways and the spring-wireways traversed by the rear lugs of the lid, substantially as described.

2. The combination, with the top of a burial casket or case, of a sliding face-lid, raceways, inclined planes for lifting the front end of said lid into and supporting it in its closed position, and springs for lifting the rear end of the lid into and locking it in its closed position, substantially as described.

JOSEPH H. WALKER.
